SCRAPER

John Edward Dahl, Rockland, Mich.

Application June 1, 1939, Serial No. 276,865

5 Claims. (Cl. 30—124)

This invention relates to an improved form of scraping tool particularly adapted for use in cleaning poultry houses.

- It is a primary aim of this invention to provide a tool especially designed and adapted for scraping and cleaning the dropping boards and floors of poultry houses, so constructed that the forward edge or either side edge of the tool may be employed as the scraping edge.
- Still a further aim of the invention is to provide a tool having a head so constructed that when either of the side edges or the forward edge is used for scraping a back wall is provided for collecting and holding the scrapings on the tool head.

Other objects and advantages of the invention will hereinafter become more fully apparent from the following description of the drawing, which illustrates a preferred embodiment thereof, and

- wherein:
- Figure 1 is a top plan view of the tool,
- Figure 2 is a longitudinal vertical central sectional view, partly in elevation, of the same, and
- Figure 3 is an end view in elevation looking toward the head of the tool.

Referring more particularly to the drawing, wherein like reference characters designate like or corresponding parts throughout the different views, 10 designates generally the tool formed of the head 11, and the handle 12.

Head 11 comprises an elongated plate 13 having an upturned end 14 forming the back wall of the tool. The opposite end 15 and the longitudinal edges 16 of the plate 13 are preferably sharpened to form scraping edges. A partition or central wall 17 rises from the plate 13 and extends the length thereof, as best seen in Figure 2. The partition or wall 17 may be secured in any manner to the plate 13 and to the inner side of the back wall 14, as by means of welding. As best seen in Figure 2, the partition 17 extends the length of the plate 13 and has its upper edge rounded at its back end to connect with the intermediate portion of the upper edge of the back wall 14. Partition 17 is provided at its opposite end with the tapered edge 18 which tapers to a point at the edge 15. The back wall 14, as best seen in Figure 3, has an arcuately shaped upper edge and is also provided with a centrally disposed opening 19 which is bisected by the partition 17.

Handle 12 is provided with the split tapered end 20 which extends through opening 19 and which is adapted to be disposed with its corresponding sections engaging opposite sides of the

partition 17. Handle 12 is secured to the head 11 by means of fastenings such as the rivets 21 which extend through the sections of the tapered end 20 and through the partition 17 to mount the handle 12 at an angle to the plate 13.

From the foregoing it will be seen, that the scraping edge 15 may be readily used for scraping a floor or other surface by means of a forward and backward motion and when thus used the back wall 14 will form a stop or abutment for the scrapings which are directed onto the plate 13. In cleaning dropping boards of poultry houses it is usually not convenient to position the scraping tool so that its forward scraping edge can be moved longitudinally of the board and for such work the tool 10 is adapted to be positioned transversely of the dropping board and moved longitudinally thereof using either of the longitudinal scraping edges 16 for scraping during this right or left movement. When either of the edges 16 are thus employed, the central longitudinal partition 17 forms the back wall or abutment to collect and retain the scrapings on either half of the plate 13.

Various modifications and changes in the precise construction and arrangement of the parts forming the scraping tool are contemplated and may be resorted to and the right is reserved to make such variations as fall within the spirit and scope of the invention as hereinafter defined by the appended claims.

I claim as my invention:

1. A device of the class described comprising a scraper head including a longitudinal plate having an upturned end, the opposite end and longitudinal edges of the plate being sharpened to provide scraping edges, a longitudinal wall rising from said plate and disposed intermediate of its longitudinal edges, said wall extending from said upturned end to the opposite forward edge of said plate, and a handle secured to said wall and extending outwardly through said upturned end, said handle being disposed at an angle to the plate.

2. A scraping tool comprising a scraping head comprising a plate having an upturned end, forming a back wall, a partition rising from said plate and disposed longitudinally thereof, the opposite end and side edges of the plate forming scraping edges, and a handle secured at one end to said head.

3. A scraping tool comprising a base portion, a wall formed integral with and rising from one end of said base portion, the opposite end and longitudinal edges thereof being sharpened to

form scraping edges, and said base portion being provided with an upwardly projecting longitudinally disposed partition extending the length thereof.

5. 4. A scraping tool comprising a head including a plate having an upturned end forming a rear wall, the opposite end and longitudinal edges of said plate forming scraping edges, a wall rising from said plate and disposed longitudinally and centrally thereof, said longitudinal wall extending the length of the plate and being provided with tapered ends, and a handle having a split

end secured to said longitudinal wall and extending outwardly through said upturned end, said handle being disposed at an angle to the plane of the plate.

5. A scraping tool comprising a head having a 5 relatively flat base portion, the side edges of the base portion being sharpened to form scraping edges, and a longitudinal wall rising from said base portion and disposed between said side edges and forming a back wall for both of said scraping 10 edges.

JOHN EDWARD DAHL.
